UNITED STATES PATENT OFFICE

2,279,290

AUTOMOBILE DOOR LATCH

Holden W. Rightmyer, Toledo, Ohio, assignor to
The American Swiss Company, Toledo, Ohio,
a corporation of Ohio

Application September 30, 1939, Serial No. 297,269

7 Claims. (Cl. 292—221)

This invention relates to door latches but particularly to latches for use on motor vehicles, and an object is to produce a new and improved door latch structure in which the bolt nose is pivotally mounted on the case plate and in which provision is made for compensating against wear of the pivotal mounting, thereby to eliminate rattles and vibration, and further in which the movement of the bolt nose to latching position is cushioned so that a stop is provided for the movement of the bolt nose in a latching direction.

This application constitutes a continuation-in-part of my co-pending application, Serial No. 225,379, filed August 17, 1938, now Patent No. 2,178,530, October 31, 1939.

For purposes of illustration but not of limitation an embodiment of the invention is shown on the accompanying drawing in which

Figure 1 is a side elevation of a door latch and its keeper, portions of the structure being broken away, such, for example, as the inside operated remote control unit and the key-actuated dogging mechanism;

Figure 2 is a transverse sectional view substantially on the line 2—2 of Figure 1;

Figure 3 is a fragmentary elevation of the outer side of the selvage plate showing the pivot, bolt structure parts being broken away to show the latch supporting pivot pin;

Figure 4 is a transverse sectional view on the line 4—4 of Figure 3; and

Figure 5 is a transverse sectional view on the line 5—5 of Figure 3.

The illustrated embodiment of the invention comprises a latch bolt casing having a main plate 10 which is mounted in any suitable manner on the vehicle door. The main plate has an outwardly inclined face or selvage plate 11 formed with an opening 12 to admit a pivoted latch bolt 13 which, as indicated in Figure 2, is adapted to cooperate with the keeper 14 suitably secured by screws 15 to the body structure 16 of the vehicle. The keeper includes an outwardly extending ridge 17 which is adapted to cooperate with the bolt 13 to provide the usual safety catch and spaced laterally from the ridge 17 and projecting a greater distance from the body structure 16 is a ridge 18 with which the latch bolt engages when the door 19 is fully closed. Only portions of the door 19 and body 16 are illustrated but these will be sufficient to illustrate the manner in which the parts are mounted in position of use.

The latch bolt 13 comprises a pair of side walls 20 and 21, a curved keeper engaging wall 22 and

5 a curved outer wall 23, which initially engages the keeper upon slamming of the door. The bolt 13 is pivotally mounted on the pin 24 which extends through openings in the inner end of the bolt and also through openings formed in laterally spaced ears 25 and 26 which are preferably struck out of the case plate 10. The pin 24 is formed of metal harder than that of which plates 10 and 11 are formed, and is provided at one end with a head 27 and has its opposite end upset as indicated at 28, a washer 29 being interposed between the upset end and the adjacent ear 26. As particularly shown on Figures 4 and 5, the washer 29 and head 27 are generally annular in shape but each is formed with a flattened portion 30 which abuts against the face plate 11 for convenience in assembly.

Directly in rear of the head 27 and washer 29 and forming a back therefor is an embossed portion 31 extending outwardly from the main plate 10 and positioned to absorb some of the shock imparted to the pin 24 by the latch bolt 13 during the slamming of the door or other actuation of the latch bolt.

25 Spaced outwardly from the pin 24 and extending through the side walls 20 and 21 of the latch bolt is a pin 32 having upset ends 33. The pin 32 engages in a groove 34 of a bolt plate extension 35 which extends inwardly and rearwardly as indicated on Figure 2 and has a strengthening rib 36. The extension 35 is integral with the bolt plate 37 which is mounted for sliding movements over the main plate 10. A spiral spring 38 has one end anchored to the main plate 10 and the opposite end of the spring 38 engages an ear 39 struck out of the bolt plate 37. It will be apparent that the spring 38 urges the bolt plate 37 to the left of Figure 1 and yieldingly urges the latch bolt 13 to its normal or projected latching position. Guiding of the bolt 37 is accomplished by a stud 40 which is secured to the main plate 10 and has its shank disposed in a longitudinally elongate slot 41 formed in the bolt plate. The stud 40 cooperates with the slot 41 in limiting the movement of the bolt plate 37.

Interposed between the bolt plate 37 and the main plate 10 is a slide 50 which is formed with a longitudinally elongate slot 51 in which the shank of a stud 52 secured to the main plate 10 is disposed, a spring washer 53 being disposed between the head of the stud 52 and the plate 50 for preventing rattling of the parts. The slide 50 has a lug 50' projecting outwardly from an upper portion thereof and the lug 50' projects

into a longitudinally elongate slot 51' formed in the bolt plate 37.

Pivotedly connected to the outer end of the slide 50 is a link 53 which extends to a suitable remote control mechanism (not shown) disposed on the inside of the door and which has the usual operating handle for retracting the latch bolt and for actuating the slide to dog or block movement of the outside operated handle as will hereinafter appear.

Formed on the forward end of the slide 50 is a finger 54 which is movable into a position beneath an arm 55 of the outside operated roll back 56 which is formed with a squared opening 57 to receive the handle shaft (not shown) equipped with an operating handle arranged on the outside of the door as will be readily understood by those skilled in this art.

The roll back 56 has a retracting arm 58 which is engageable with a flange 59 on the bolt plate 37 so that upon clockwise rotation (Figure 1) of the roll back, the bolt plate 37 is moved to the right of the figure thereby retracting the pivoted latch bolt 13 as will be readily understood. The detail construction of the roll back 56 is well-known to those skilled in this art and since it forms no part of the present invention, detail description and illustration is not considered necessary. A spiral spring 60 mounted on the main plate 10 engages the roll back for holding the parts thereof in the desired position and eliminating rattles.

In order to cushion the movement of the latch bolt 13 to latching position, a flange 61 projects laterally from the side wall 21 of the latch bolt. The inner face of the flange 61 is adapted to engage a rubber bumper 62 which is mounted on the face plate 11. As shown in Figure 3, a notch 63 projects from the opening 12 in the face plate 11 to enable mounting of the bumper which is made up of a body portion 62, reduced neck 64 and an outer annular head 65. In mounting the bumper, the neck 64 is forced into the notch 63, the head being disposed on the outer side of the face plate and the rubber body 62 on the inside of the face plate.

In the operation of the above described latch, it will be apparent that the latch bolt can be retracted from the outside of the door by operation of the roll back 56. By rotating the roll back, the arm 58 engages the shoulder or flange 59 and forces the bolt plate 37 to the right of Figure 1 against the force of the spring 38 and thereby causing the latch bolt 13 to rock upon its pivot 24 through the connections described.

In order to retract the latch bolt from the inside of the door, the link 53 is moved to the right of Figure 1 thereby causing movement of the slide 50 and retraction of the bolt plate 37 through the lug 50' upon engagement thereof with the inner end of the slot 51'.

When it is desired to dog the outside operated roll back 56, the link 53 is moved in a non-bolt retracting direction or to the left of Figure 1 thereby moving the finger 54 beneath the arm 55 of the roll back and accordingly blocking movement of the latter. When the roll back is dogged, the lug 50' is disposed in abutting relation to the forward end of the slot 51' so that upon slamming of the door, the bolt plate 37 is moved to the right of the figure, thereby forcing the lug 50' to the right. This action effects movement of the finger 54 away from the roll back. It will thus be apparent that slam-unlocking is obtained.

It is to be understood that numerous changes in details of construction, arrangement and oper-

ation may be effected without departing from the spirit of the invention especially as defined in the appended claims.

What I claim is:

5. 1. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, and members on opposite end portions of said pin to retain same on said ears respectively, said members being adapted to abut against the adjacent plate member in the event of enlargement of the holes in the ears due to wear.
10. 2. In a vehicle door latch, a main plate, a selvage plate projecting at an angle from one side of said main plate and having an opening therein, said plates being formed of sheet metal, a bolt nose mounted for pivotal movements to and from latching position through said opening, a pair of laterally spaced ears carried by said selvage plate, a pin formed of metal harder than the metal of which said plates are formed passing through holes in said ears providing a pivotal mounting for said bolt nose, and members on opposite end portions of said pin to retain same on said ears, said members being adapted to abut against the adjacent plate member in the event of enlargement of the holes in the ears due to wear.
15. 3. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin formed of metal harder than the metal of which said plates are formed passing through holes in said ears providing a pivotal mounting for said bolt nose, and members on opposite end portions of said pin to retain same on said ears, said members being adapted to abut against the adjacent plate member in the event of enlargement of the holes in the ears due to wear.
20. 4. In a vehicle door latch, a main plate, a selvage plate projecting at an angle from one side of said main plate and having an opening therein, said plates being formed of sheet metal, a bolt nose mounted for pivotal movements to and from latching position through said opening, a pair of laterally spaced ears carried by said selvage plate, a pin formed of metal harder than the metal of which said plates are formed passing through holes in said ears providing a pivotal mounting for said bolt nose, and members on opposite end portions of said pin to retain same on said ears, said members being adapted to abut against the adjacent plate member in the event of enlargement of the holes in the ears due to wear.
25. 5. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
30. 6. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
35. 7. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
40. 8. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
45. 9. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
50. 10. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
55. 11. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
60. 12. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
65. 13. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
70. 14. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.
75. 15. In a vehicle door latch, a main plate, a selvage plate projecting at an angle from one side of said main plate and having an opening therein, a bolt nose mounted for pivotal movements to and from latching position through said opening, a pair of laterally spaced ears carried by said selvage plate, a pin passing through holes formed therefor in said ears providing a pivotal mounting for said bolt nose, members on opposite end portions of said pin to retain same on said ears respectively, and a projection on one of said plates for each member and against which same is adapted to abut upon enlargement of the holes in the ears due to wear.

adapted to abut in the event of enlargement of the holes in the ears due to wear.

6. In a vehicle door latch, a main plate, a flanged face plate, on said main plate, a spring tensioned bolt nose movable through an aperture in said face plate, ears carried by one of said plates, a pivotal pin for said nose, means to retain the pin on said ears, and means on one of said plates against which the retaining means of said pin is adapted to impinge to absorb

shock imposed upon the pin during slamming of the door.

7. A vehicle door latch in accordance with claim 6, wherein the means against which the retaining means of the pin is adapted to impinge embodies a portion of concavo-convex cross-section integral with said one of said plates and which has its convex side confronting the retaining means for engagement with the latter.

HOLDEN W. RIGHTMYER.
